SURGICAL BANDAGE IMPREGNATING DEVICE

John Zaccheo, New Rochelle, N. Y.

Application November 21, 1939, Serial No. 305,570

9 Claims. (Cl. 91—32)

This invention relates to apparatus and methods for impregnating material and more particularly to apparatus for impregnating with suitable liquids bandages such as are used for binding or wrapping the legs or arms or other body parts of persons having disorders, varicose veins for instance, needing such binding; though it is noted that in some of the claims the invention is not limited to bandages or impregnating.

One object of the invention is to provide an improved device or apparatus of this kind in which strip bandage material is passed from a supply roll, through the impregnating liquid and then wound upon another roll ready for use.

Other objects of the invention are to provide an improved device of this kind in which the bandage material may be easily threaded through the apparatus and onto a take-up shaft, and to provide a suitable removable shaft for the take-up roll which may serve as a suitable handle for unrolling and applying the bandage.

Additional objects of the invention are to effect simplicity and efficiency in such methods and apparatus and to provide an extremely simple apparatus of this kind which is economical, convenient and reliable in operation, and economical to manufacture.

Still other objects of the invention will appear as the description proceeds; and while herein details of the invention are described in the specification and some of the claims, the invention as described in the broader claims is not limited to these, and many and various changes may be made without departing from the scope of the invention as claimed in the broader claims.

The inventive features for the accomplishment of these and other objects are shown herein in connection with a bandage impregnating apparatus which briefly stated, includes nested upper and lower elongated vessels and a frame therearound carrying a removable bandage supply means at one end and a take-up shaft removably mounted near the other end of the vessel. A transverse lower guide member mounted on the frame near the supply means and having a part near the bottom of the vessel to engage over the bandage, and a transverse lifting guide mounted on the frame over the vessel near the take-up shaft serve to guide bandage material from the supply means to the take-up shaft.

In the accompanying drawing showing, by way of example, one of many possible embodiments of the invention,

Fig. 1 is a plan of the apparatus;

Fig. 2 is a fragmented horizontal vertical sec-

tional view, partly in elevation, showing the apparatus with a bandage strip therein, the section being taken substantially on the line 2—2 of Fig. 1, looking in the direction of the arrows of said line;

Fig. 3 is a fragmental end view of the apparatus;

Fig. 4 is a side elevation of the lower guide member, frame parts being in section;

Fig. 5 is a similar side elevation of the lifting guide; and

Fig. 6 is a perspective view showing the take-up shaft and roll.

The bandage impregnating apparatus comprises a vessel 10 for the impregnating liquid, and if desired a temperature control means, such for instance as a lower elongated vessel 11 of heat-resistant glass adapted to receive a heat exchanging liquid of the desired temperature. As shown, a rectangular frame 12 is disposed over said vessel providing a large intra-marginal opening 13 (left of Fig. 2) about as large as and over the vessel 11. A molding 15 secured on the lower face of the frame around said opening is provided with an inner groove 16 received on the upper edge of the vessel, the molding being cut away as at 17 (Fig. 3) to accommodate the handle 18 of the vessel.

The upper container 10 is similar to and spaced from, the lower container and nested in said opening 13 and the lower container and said heat exchanging liquid and adapted to contain the impregnating liquid adapted to be warmed or cooled by heat passing through the upper container from or to said liquid of the lower vessel.

A pair of bearing ears 20 projecting outwardly and upwardly from one end member of said frame 12 have upwardly open bearing slots removably receiving a headed supply spindle 21 (Fig. 1) adapted to carry a supply roll 22 of strip bandage material to be impregnated. A pair of guide brackets 23 adjustably secured on said end member of the frame are provided with vertical guide pieces 24 adapted to engage ends of the roll.

A pair of bearing blocks 27, 28 are mounted on the side members of the frame near the other end 29 of the frame, the block 27 being provided with a bearing bore 30 opening toward the other block. The block 28 has upstanding lugs 31, 32 (Fig. 2) providing an intermediate U-shaped portion providing an upwardly open bearing recess 33 the lower part of which is aligned with said bore 30. A take-up or winding shaft 35 rotatable in said bore and recess is provided in the part adjacent to the recess 33 with a transverse

end slot 36, and with an annular groove 37 around the shaft in said recess. The lug 32 is provided with a horizontal bore 38, 39 having a small inner end 38 above the axis of the shaft and a large countersunk outer end 39. A detent pin 40 in said small end 38 and loosely engaged in said groove 37 has a head 41 at its outer end in the inner end part of the countersink 39 and engaged by a helical spring 43 compressed between said head and a threaded plug 44 in the outer end of the countersink for yieldably holding the pin in said groove, whereby the shaft is yieldably held against outward and upward movement, and may be easily removed from the bearing blocks.

A crank handle 45 has a hub 46 removably frictionally held on the slotted end of the shaft and carrying a transverse pin 47 engaged in said end slot 36, whereby revolution of the crank handle constrains the shaft to rotate. Said shaft has a long longitudinal slot 48 intermediately therein adapted to receive the end of a bandage to facilitate winding the bandage from said spindle 21 onto the shaft.

An approximately U-shaped depressing guide member 50 (Figs. 2 and 4) near the supply roll 21 comprises upright arms 51 within the vessel having hooked ends 52 disposed over the edge of the vessel and removably engaged in the adjacent bores 53 in the frame. Said guide member 50 also comprises a straight horizontal transverse lower yoke 55 near the bottom 56 and sides of the upper vessel and is adapted to engage over an intermediate part 22a of the bandage material passing from the supply to the take-up shaft, to hold it deep in the impregnating liquid. A handle for said guide member comprises a thin horizontal bar 57 having upper and lower rounded edges and provided with vertical end grooves 58 (Fig. 1) in which the upper intermediate part of the arms 51 just below the hooked end are secured.

A transverse lifting or supporting guide near the take-up shaft comprises a wire 60, 61, 62 (Figs. 1 and 5) bent to form a middle horizontal supporting and guiding part 60 of a length substantially equal to the width of the bandage, upright guide arms 61 at the ends of the supporting part extending above the level of the top edge of the vessel, the end parts 62 of said wire being bent outwardly and slightly toward the take-up shaft and then turned downwardly and removably received in the adjacent bores in the side members of the frame. Said supporting part 60 raises the bandage as it passes to the take-up roll 64, scraping off excess liquid and holding the bandage in position to be cut across with scissors between said part 60 and the shaft when enough has been received on the take-up roll, whereupon the take-up shaft may be removed against the yielding action of said pin 40, 60 after which another similar shaft may be placed in the bearings, the detachable crank handle 45 applied thereto, the cut end of the bandage threaded into the slot 48, adapting the apparatus for further operation. The detached take-up shaft with the roll 64 of bandage material thereon, may then serve as a convenient handle to hold the impregnated bandage roll while the bandage is being wound around the limb or part to which it is applied.

When the bandage material of the roll 22 is exhausted, the spindle 21 may be removed and a new roll slipped in its place. The depressing guide means 50 is then removed and the bandage strip passed over the supporting part 60 and

threaded into the slot 48, after which a turn or two of the crank will wrap the strip about the shaft and thus secure the same to the shaft. The guide means 50 is then replaced to the position of Fig. 2, causing the traveling strip to be immersed in the impregnating liquid.

During the operation of treating the bandage with the impregnating fluid and during the winding operation, the treated bandage 22, is passed over the lifting and supporting guide 60, 61 and 62, as disclosed in Figs. 1 and 5, and the bandage guide portion 60, Fig. 5, tends to act as a doctor or scraper, as well as a guide, to remove excess impregnating fluid from the bandage. The removed excess fluid falls back into the vessel 10.

In some forms of treating bandage material, the medicinal fluid may have to be heated to reduce its viscosity, and to hasten its absorption into the bandage and under this condition, sufficient water may be placed in the lower vessel 11, and the device placed upon a heating means, so that the impregnating fluid may be controllably heated to desired temperatures, during the bandage impregnating operation.

From the foregoing, it will be noted that the treated bandage may be treated, wound into a roll 22, and applied to the patient, without the necessity of touching the bandage itself by the hands, thus preserving the bandage from unsanitary contacts.

The invention claimed is:

1. A bandage impregnating apparatus comprising in combination, an elongated vessel; a frame therearound; removable bandage supply means at one end of said frame; a pair of bearing blocks on the side members of the frame near the other end of the frame; one of said blocks being provided with a bearing bore opening toward the other block; said other block having upstanding lugs providing an intermediate U-shaped portion providing an upwardly open bearing recess aligned with said bore; a take-up or winding shaft in said bore and recess and provided in the part adjacent to the recess with a transverse end slot, and with an annular groove around the shaft in said recess; one of said lugs being provided with a horizontal bore having a small inner end above the axis of the shaft and a large countersunk outer end; a detent pin in said small end loosely engaged in said groove and having a head at its outer end in the inner end part of the countersink; a threaded plug in the outer end of the countersink; a helical spring compressed between said head and plug for yieldably holding the pin in said groove; whereby the shaft is yieldably held against outward and upward movement, and may be easily removed from the bearing blocks; and means for guiding bandage material from the supply means through the vessel to the shaft.

2. An impregnating apparatus comprising in combination, an elongated vessel; a frame therearound; removable strip supply means at one end of said vessel; a take-up shaft removably mounted near the other end of the vessel; a transverse guide member mounted on the frame near the supply means; a transverse lifting guide mounted on the frame over the vessel near the take-up shaft and having a part for engaging under the strip; the frame being provided with a pair of small bores in the top face of the side members of the frame near the respective ends of the upper vessel; said guide member comprising an approximately U-shaped wire near the supply comprising upright arms within the vessel having hooked ends disposed over the edge of

the vessel and removably engaged in the adjacent bores; said wire comprising also a straight horizontal transverse lower yoke near the bottom and sides of the vessel and adapted to engage over the intermediate part of strip passing from the supply to the take-up shaft, to hold it deep in the impregnating liquid; and a handle for said guide member comprising a thin horizontal bar having upper and lower rounded edges and provided with vertical end grooves in which the upper intermediate part of each arm just below the hook is secured.

3. An impregnating apparatus comprising in combination, an elongated vessel; a frame there-around; removable strip supply means at one end of said vessel; a take-up shaft removably mounted near the other end of the vessel; a transverse guide member mounted on the frame near the supply means and having a part near bottom of the vessel to engage over the strip; a transverse lifting guide near the take-up shaft comprising a wire bent to form a middle horizontal supporting and guiding part of a length substantially equal to the width of the strip, upright guide arms at the ends of the supporting part extending above the level of the top edge of the vessel; the end parts of said wire being bent outwardly and slightly toward the take-up shaft and then turned downwardly; the frame being provided with bores adjacent to the shaft for removably receiving the down-turned end parts; said supporting part of the lifting guide raising the strip as it passes to the take-up roll, scraping off excess liquid and holding the strip in position to be cut across with scissors when enough has been received on the take-up roll.

4. A bandage impregnating apparatus comprising, in combination, a lower elongated vessel of heat-resistant glass adapted to receive a heat exchanging liquid of the desired temperature; a rectangular frame disposed over said vessel and forming an intra-marginal opening about as large as and over the vessel; a molding secured on the lower face of the frame around said opening and provided with an inner groove received on the upper edge of the vessel; an upper container similar to and spaced from, the lower container and nested in said opening and the lower container and said liquid and adapted to contain an impregnating liquid adapted to be warmed or cooled by heat passing through the upper container from or to said liquid of the lower vessel, a bandage supply, and take up means and means

for guiding bandage through the upper vessel mounted on said frame; the frame and vessels being separable from each other.

5. A bandage impregnating apparatus comprising in combination, a vessel; a frame there-around; and a bracket adjustably secured on said frame and adapted to engage an end of a bandage supply roll and provide a braking effect thereto.

6. A bandage impregnating apparatus comprising in combination, a vessel; a supply roll of bandage; means for mounting the roll for unrolling the bandage and near one margin of the vessel; a means for guiding the bandage through the vessel; a pair of brackets adjustably secured 15 near said margin and provided with vertical faces engaging the ends of said roll, for retarding rotation of the roll and keeping the bandage taut and guiding the bandage drawn through the vessel.

7. An impregnating apparatus comprising in 20 combination, a vessel; side members attached thereto; a strip supply means adjacent to the vessel; a transverse depressing guide member mounted over the vessel, said guide member comprising a horizontal part with upwardly extending side arms within the vessel having ends bent outwardly and then downwardly; said side members being provided with vertical bores to receive said ends; and a handle for said guide member.

8. An impregnating apparatus comprising in combination, a vessel; a member attached thereto; a strip supply means at one end of the vessel; a depressing guide extending downwardly into the vessel; and a lifting guide mounted over the vessel and comprising a wire bent to form a middle supporting horizontal part, upright guides at the ends thereof; the end parts of said wire being bent outwardly and then turned downwardly; said member being provided with vertical bores adapted to receive said ends.

9. A bandage impregnating apparatus comprising in combination a vessel; a removable bandage supply means at one end of said vessel; a pair of opposed bearing blocks near the other end of the vessel; one of said blocks being provided with a bearing bore opening toward the other block; the other block being provided with a U-shaped opening the lower part of which is aligned with said bore; a take-up shaft in said bore and recess, said shaft being provided with an annular groove at the portion lying within said opening; and a yieldable means attached to said other block and engaging said groove.

JOHN ZACCHEO.
